US00D337589S

United States Patent [19]

Wada

[11] Patent Number: Des. 337,589

[45] Date of Patent: ** Jul. 20, 1993

[54] EARPHONE

[75] Inventor: Joh Wada, Tokyo, Japan

[73] Assignee: Sony Corporation, Tokyo, Japan

[**] Term: 14 Years

[21] Appl. No.: 797,278

[22] Filed: Nov. 25, 1991

[30] Foreign Application Priority Data

Jun. 17, 1991 [JP] Japan 3-18003

[52] U.S. Cl. D14/223
